UNITED STATES PATENT OFFICE.

JAMES E. GROSJEAN, OF LIMA, OHIO.

HEEL FOR BOOTS OR SHOES.

Application filed October 18, 1920. Serial No. 417,562.

To all whom it may concern.

Be it known that I, JAMES E. GROSJEAN, a citizen of the United States, residing at Lima, in the county of Allen and State of Ohio, have invented new and useful Improvements in Heels for Boots and Shoes, of which the following is a specification.

My present invention relates to improvements in heels for boots and shoes, and more especially to those of the so-called cushion type employing a rubber compound or composition as a constituent thereof. The object of the invention is to provide a novel and improved heel of this type which possesses increased wear resisting properties and which produces an anti-slipping or non-skid surface on its tread which will remain effective during the wear of the heel, it possesses the desired degree of resilience or elasticity and it is capable of being easily, quickly and securely fastened to the shoe by nails or equivalent fastening devices, which may be driven at the usual or any other desired points in the heel and will effectively prevent loosening of the heel or pulling of the nail heads through the heel.

The invention has the important practical advantages that it enables layers of friction fabric or fabric with interposed layers or coatings of rubber, and especially such material as reclaimed from old or discarded pneumatic tire casings to be used largely in the making of the heels, the fabric being so disposed in the heel as to produce the wear-resisting and anti-slipping properties referred to, the resilience or elasticity of the rubber layers or coatings between the plies of fabric, in conjunction with the resilience or elasticity of the body of the heel, which is preferably composed of a suitable rubber compound in molded form, affording the desired degree of resilience or elasticity for the heel, as hereinbefore referred to.

To these and other ends, the invention consists in certain improvements, which will be hereinafter more fully described, the features of novelty being pointed out particularly in the claims at the end of the specification.

50 In the accompanying drawing:—

Figure 1 represents a section taken vertically through a portion of a shoe and the heel thereon, the heel being constructed in accordance with the preferred embodiment 55 of the invention;

Figure 2 represents a transverse section

through the shoe and heel on the line 2—2 of Figure 1;

Figure 3 is a bottom plan view of the heel as shown in Figures 1 and 2;

Figure 4 is a perspective view of the heel as viewed from its upper side;

Figure 5 represents a longitudinal section taken through the rear portion of a shoe and the heel thereon, showing a half heel constructed in accordance with the present invention;

Figure 6 represents a transverse section through the shoe and heel on the line 6—6 of Figure 5;

Figure 7 is a perspective view of the half heel as shown in Figures 5 and 6 and viewed from its upper side; and

Figure 8 represents a transverse section through a heel made in accordance with another embodiment of the invention.

Similar parts are designated by the same reference characters in the several figures.

Heels or half heels embodying the present invention are suitable for use generally on boots and shoes as a substitute for the ordinary leather heel. The preferred embodiment of the invention as applied to a whole heel and also a half heel, is shown in the accompanying drawing and will be hereinafter described in detail. It is to be understood, however, that the invention is not restricted to the precise construction shown, as equivalent constructions are contemplated and these will be included within the scope of the claims.

In the present instance, wherein the improved heel is shown applied to a shoe, 1 represents a portion of the upper of the shoe and 2 the sole. The whole heel shown in Figures 1 to 4 inclusive, comprises a body 3 which is composed preferably of a rubber compound possessing the desired degree of resilience or elasticity, the body being molded in the desired form and cured. The body of the heel, according to the present invention, contains a number of plies 4 of fabric, such as canvas, impregnated with rubber or rubber cement, or having thin layers or coatings of rubber interposed between them, these layers of fabric in the finished heel being vulcanized together and embedded in the heel between the top and the tread 5 thereof. Preferably, the fabric layers or plies 4 are composed of friction fabric or fabric stock, such as that employed in the manufacture of casings of pneumatic tires, it being most ad-

vantageous to employ fabric obtained from old or discarded pneumatic tire casings, as the fabric can thus be obtained not only inexpensively, but the plies of fabric will be found firmly vulcanized together by the interposed layers or coatings of rubber. The body composed of the superposed fabric plies 4 is preferably of such a size and shape that its margin lies within the marginal edges of the heel and the marginal portions of the body composed of the fabric plies 4, preferably lies in a plane parallel to the tread 5, or substantially so, while the middle or intermediate portion of this body is bent or deflected downwardly to form a depressed portion 6. The depressed portion 6 of the fabric body is preferably formed with a perforation 7, and the mold in which the heel is formed is preferably so shaped that the plastic rubber compound which is to form the body 3 of the heel, when compressed in the mold, will cover the upper and lower sides of the marginal edges of the fabric body, and a portion of the rubber compound will be forced or extruded upwardly through the perforation 7 in the fabric body and will form a stud or nipple 8 surrounded by a concavity 9, the concavity 9 lying beneath a chamber 10 which is open at the upper side of the heel. Preferably, a plug 11 of fabric which is punched from the body in forming the perforation 7 therein, is placed in the body of the mold in alignment with the perforation 7 and the stud or nipple 8, so that in the finished heel the fabric plug 11 will be exposed or nearly exposed on the lower or tread side of the heel. Bosses 12 are also preferably molded on the lower or tread surface of the heel to provide a roughened or anti-skid surface, these bosses being preferably in the form of rosettes, as shown in Figure 3, around holes 13 which may be formed in the body of the heel below the fabric portion to receive the nails 14, or other devices for fastening the heel to the shoe. In fastening the heel to the shoe, the nails, or equivalent fastening devices, are inserted through the openings 13 and driven upwardly through the fabric body and into the sole 2, nails, when used, being usually clenched at the upper side of the sole. These nails are driven until the heads thereof come up against the under side of the fabric body, the latter then providing a securing means for the heel which will effectually withstand pulling of the nail heads therethrough.

A heel constructed in the manner described can not only be easily, quickly and firmly secured to the shoe, but the fabric body contained within the heel provides a wear-resisting and non-skid surface on the tread of the heel, after the latter has been worn away to some extent, it being obvious that the depressed intermediate portion 6 of the fabric body will become exposed at the tread of the heel, after the latter has been worn to some extent, and owing to the inclination of this depressed portion 7 of the fabric relatively to the plane of the tread surface of the heel, the fibres or threads comprising the fabric plies will be presented substantially or approximately endwise to the tread surface, thus insuring maximum wear-resisting properties. The marginal portions of the fabric body and through which the nails or other securing devices pass, are located at a greater distance from the tread surface of the heel and, in consequence, the intermediate depressed portion 6 of the fabric body will become exposed at the tread surface, while the marginal portions of the fabric body and the heads of the securing nails remain covered. When, as is preferable, the fabric plug 11 is employed, this plug will provide a wear-resisting and non-skid surface on the tread of the heel when the heel is new. By providing the concavity 9 around the nipple 8 and also the chamber 10, the middle or central portion of the heel is rendered more elastic or resilient, thus providing a cushioning action to a desirable degree. And furthermore, this central portion of the heel will not wear away as rapidly as the remainder or margin of the heel, thus leaving a raised center for the heel which is relieved, however, from grinding action by the resiliency of this portion of the heel, and when the heel is nearly worn out, the center thereof has a greater cushion effect than it has when the heel is new, but notwithstanding the consequent reduction in the thickness of this part of the heel, such part of the heel is sufficiently reinforced by the depressed portion 6 of the fabric body. The upwardly projecting nipple 8 also serves as a stop to limit the upward flexing of the middle of the heel, should the wearer step upon a pebble or other sharp or raised surface, thus avoiding breakage or other damage to the heel. It will be understood that while the securing nails may be driven through the nail-receiving holes 13, which may be located in a definite position so that all of these nails may be driven simultaneously, other or additional securing nails may be driven, if desired, at any other points, the fabric body 4 being readily puncturable by the nails, although it is capable of effectually preventing pulling of the nail heads therethrough.

In the embodiment of the invention shown in Figures 5 to 7 inclusive, is shown a half heel 14 which may be used when desired, it being shown secured to the underside of the heel lifts 15 after a suitable number of heel lifts have been removed. In this instance, the heel is composed of a body of rubber compound molded in the desired shape and having a fabric body 4^a corresponding substantially to the fabric body 4, described above. In this instance, however, the upper

side of the fabric body 4^a may be exposed at the top of the heel so as to lie directly against the lowermost heel lift of the shoe, and the central depressed portion 6^a of the fabric body may be inclined at a greater angle to the plane of the tread of the heel, as shown. The stud or nipple 8^a which protrudes upwardly through the central perforation 7^a in the fabric body, preferably lies closely adjacent to the underside of the lowermost heel lift, so that this nipple will bear against the heel lift and thus avoid undue strain or upward deflection of the central portion of the heel, should the latter be brought to bear upon a pebble or other sharp or upstanding projection at the center of the heel. The depressed portion 6^a of the fabric body provides a concavity 9^a which surrounds the nipple 8^a, thus affording increased resilience or elasticity for the center of the heel, although this portion of the heel which is, in consequence, of reduced thickness, is reinforced by the fabric body. The nails 14^a or equivalent devices which secure the heel to the shoe, may be driven in the same manner as described in connection with the nails 14.

Instead of initially forming the bottom or tread of the whole heel or half heel flat, the central portion thereof may be crowned or bowed downwardly as shown at 16 in Figure 8, this crowned or downwardly bowed portion preferably extending at its apex to the plane in which lie the embossed rosettes surrounding the nail-holes, it being understood that this crowned portion of the heel lies immediately below and in line with the downwardly deflected portion of the fabric body, the cavity and the nipple. By this construction, the heel throughout its period of wear, possesses the desired degree of cushioning action and moreover, wearing away of the tread of the heel is resisted or retarded.

In each instance, it is to be understood that the rubber compound composing the body of the heel is molded while the fabric body is in place, the entire structure being then cured, as a result of which the fabric body and the rubber composition body of the heel are securely vulcanized together.

By providing a rubber heel with a fabric body such as herein described, a wear-resistant and anti-slipping surface becomes exposed at the tread of the heel as the latter becomes worn, and even though the heel may wear to a considerable extent, the exposed portion remains firmly secured within the heel by the marginal portion of the fabric body which remains unexposed and fastened by the nails or fastening devices. Also, while the center of the heel is rendered more resilient or elastic, owing to the reduction in thickness thereof, this portion of the heel is reinforced by the central or

depressed portion of the fabric body which acts as a supporting arch. By dispensing with the use of washers to secure the nail heads, important practical advantages are obtained, as the fastening nails may be driven at any desired points, there is no danger of spoiling the heel during the operation of driving the nails, and moreover, the objections resulting from the exposure of such washers as the heel becomes worn, are avoided, it being a well known fact that when the washers of ordinary heels become uncovered by wear, the cushion effect is entirely lost or destroyed.

I claim as my invention:—

1. A heel for boots or shoes comprising a body composed of flexible material forming a substantially flat tread, a yieldable body composed of multiple plies of fabric having a portion within the margin thereof offset relatively to its marginal portions and toward the tread and forming a cavity above it, said offset portion providing an upwardly yieldable cushion and constituting a wear-resisting medium adapted to become exposed at the tread by wear of the latter prior to the exposure of the marginal portions of said fabric body.

2. A heel for boots or shoes comprising a body composed of flexible material forming a substantially flat tread, and a body composed of multiple plies of fabric having rubber incorporated therewith, the marginal portion of said body being puncturable by nails and forming means for securing the heel to a boot or shoe and the portion of said fabric body within the marginal portion being relatively offset toward the tread to form an upwardly yieldable cushion and to provide a wear-resisting medium which will become exposed at the tread by wear of the latter prior to the exposure of the marginal portion of said fabric body.

3. A heel for boots or shoes comprising a molded rubber body having a tread, the marginal portion of which is substantially flat and a multiple-ply fabric body vulcanized thereto, the intermediate portion of the fabric body being depressed toward the tread of the heel and having a cavity formed above such depressed portion.

4. A heel for boots and shoes comprising a rubber body having a tread, the marginal portion of which is substantially flat and a multiple-ply fabric body vulcanized thereto, the marginal portion of the fabric body lying substantially in parallelism with the relatively flat marginal portion of the tread of the heel and providing a fastening means therefor and the intermediate portion of the fabric body being depressed relatively to its marginal portion toward the tread and having a cavity located above it.

5. A heel of the character described comprising a rubber body molded into the

form of a heel having a substantially level tread surface and a fabric body vulcanized thereto and having an intermediate depressed portion which is inclined toward and relatively to the tread surface and provided with a perforation through which a part of the rubber body extrudes.

6. A heel of the character described comprising a rubber body having a substantially flat tread and a fabric body vulcanized thereto and having a perforation through which a portion of the rubber body extrudes and forms an upwardly-projecting nipple to act as a stop to limit the upward displacement of the perforated portion of the fabric body and the adjacent portion of the rubber body.

7. A heel of the character described comprising a rubber body having a substantially flat tread and a fabric body vulcanized thereto and having an intermediate depressed portion provided with a perforation through which a part of the rubber body protrudes upwardly to form a nipple, the latter being surrounded above the depressed portion of the fabric body by a cavity.

8. A heel of the character described comprising a body of vulcanizable material molded into the form of a heel having a substantially plane tread, and a fabric body vulcanized thereto, the fabric body having marginal nail-receiving portions lying substantially in parallelism with the tread of the heel and having an intermediate portion depressed toward the tread and having a cavity above it.

9. A heel of the character described comprising a body of vulcanizable material molded into the form of a heel having a substantially flat tread, and a fabric body vulcanized thereto, the fabric body having marginal nail-receiving portions and an intermediate portion depressed toward the tread relatively to said marginal portions

and provided with a perforation through which part of the said vulcanizable material projects upwardly to form a nipple, said nipple being surrounded above said fabric body by a cavity.

10. A heel for boots or shoes comprising a body of vulcanizable material forming a substantially flat tread surface and a fabric body vulcanized thereto and having a portion thereof depressed toward the tread surface and provided with a perforation, and a fabric plug embedded in the tread surface opposite to the perforation in the fabric body.

11. A heel for boots and shoes comprising a body composed of vulcanizable material and a fabric body vulcanized thereto, said vulcanized body having a cavity in its upper side and the fabric body having a portion below said cavity depressed toward the tread of the heel, said depressed portion of the fabric body having a perforation, and a plug of wear-resisting material embedded in the tread below and opposite to said perforation and cavity.

12. A heel for boots and shoes comprising a body composed of vulcanizable material and a fabric body vulcanized thereto, said vulcanizable body having a cavity therein and the fabric body having a portion thereof below said cavity depressed toward the tread and provided with a perforation, a portion of the material composing the vulcanizable body extending upwardly through said perforation and forming a nipple which projects into said cavity, and a fabric plug embedded in the tread of the heel and below and opposite to said perforation, nipple and cavity.

In testimony whereof I have hereunto set my hand in presence of two subscribing witnesses.
